UNITED STATES PATENT OFFICE.

EDWARD J. ABBOTT, OF MISSION JUNCTION, BRITISH COLUMBIA, CANADA.

STAMP-AFFIXING AND ENVELOP-SEALING MACHINE.

1,055,692.

Specification of Letters Patent. Patented Mar. 11, 1913.

Application filed April 27, 1911. Serial No. 623,634.

To all whom it may concern:

Be it known that I, EDWARD J. ABBOTT, a subject of the King of England, and a resident of the city of Mission Junction, Province of British Columbia, and Dominion of Canada, have invented certain new and useful Improvements in Stamp-Affixing and Envelop-Sealing Machines, of which the following is a specification.

10 My invention relates to improvements in stamp affixing and envelop sealing machines and has for its objects the production of a machine of this character which will be of improved construction and efficient in operation.

15 Other objects will appear hereinafter.

With these objects in view my invention consists in a stamp affixing and envelop sealing machine characterized as above mentioned and in certain details of construction and arrangements of parts all as will be hereinafter more fully described and particularly pointed out in the appended claims.

25 My invention will be more readily understood by reference to the accompanying drawings forming a part of this specification, and in which,

Figures 1 and 2 are elevations of the respective sides of a stamp affixing and envelop sealing machine embodying my invention, Fig. 3 is a top plan view thereof,

Fig. 4 is a vertical section taken on substantially line $z-z$ of Fig. 3, Fig. 5 is a vertical section taken on substantially line $y-y$ of Fig. 4, Fig. 6 is an enlarged detail fragmentary section taken on substantially line $x-x$ of Fig. 3, Fig. 7 is an enlarged detail fragmentary section taken on substantially line $w-w$ of Fig. 4, Fig. 8 is a

35 sectional plan view of the well included in the stamp licking or moistening mechanism detached, Fig. 9 is an end elevation of the machine illustrating the mechanism for tilting the envelop-flap moistening well, parts of the machine being omitted, Fig. 10 is a top plan view of the well included in the envelop-flap moistening mechanism, detached, Fig. 11 is a sectional detail of the

40 envelop gripping and feeding rollers, also illustrating the method by which the flap of the envelop is moistened, Fig. 12 is an enlarged detail section of the stamp ribbon or strip feeding and cutting mechanism

taken on substantially line $v-v$ of Fig. 3, 55 Fig. 13 is a central section of the construction shown in Fig. 12, Fig. 14 is an enlarged detail top plan view of a portion of the gearing included in the construction, and Fig. 15 is a section taken on substantially line $u-u$ of Fig. 14.

The preferred form of my construction as illustrated in the drawings comprises a frame 1 in which the several parts of mechanism are attached and mounted, this frame 65 being designed to rest upon a suitable support such as a table or desk so that the machine will be positioned for manual operation.

Arranged in the frame 1 at one end thereof is an envelop magazine 2, the latter being pivotally mounted upon inwardly projecting pins 2' provided in the opposite sides of said frame. The magazine 2 is of any suitable dimensions, the same being 75 however of such a size as to adapt the same to receive an envelop of standard or conventional dimensions. The free or inner end of the magazine 2 rests upon a roller 3, the extremities of the shaft 4 of said roller being mounted as will be hereinafter described so as to permit of vertical movement of said roller. In order to yieldingly maintain said end of said magazine in position upon the roller 3, a leaf spring 5 is provided which rests against the upper end of said magazine, said spring 5 being fixed at its lower end to a transversely extending bar 6 provided in the frame 1. Provided within the magazine 2 are centering guides 70 80 85 90 95 95 flexibly depending from the upper edges of the sides of said magazine and adjustable at their lower ends by means of screws 9 which engage against bars 8 connecting the lower ends of said guides at corresponding ends or sides of said magazine.

The magazine 2 is open at its upper end and also at its bottom except for the ledge 10 which projects inwardly across the back of said magazine. With this arrangement 100 it will be observed that the envelops resting in the magazine will be supported at their rearward edges upon said ledge 10 and at their forward edges upon the roller 3.

Arranged below the magazine 2 in close 105 proximity with the bottom thereof is a transversely extending plate 11 the extremities of which are reciprocally mounted in

2
guide slots 12 provided in the opposite sides of the frame 1. The envelopes positioned in the magazine 2 are arranged with their flaps downwardly and so that the latter rest upon the roller 3. With this arrangement upon reciprocatory movement of the plate 11, the lowermost envelop in the magazine 2 will be engaged and withdrawn from the magazine upon each reciprocation of said plate 10 by reason of the forward edge of the latter engaging under the flap of said envelop as clearly shown in Fig. 11. Said edge of said withdrawing plate is beveled as clearly illustrated in Fig. 4 so that upon reciprocation thereof as mentioned, said edge will readily pass under the forward edge of the magazine effecting elevation of the latter to permit of the passage of the envelop carried by said plate and preventing withdrawal of the envelopes positioned above that engaged. Said plate will deliver said envelop to superimposed coöperating rollers 13 and 14, the shafts 15 and 16 respectively of which are rotatably mounted in the opposite sides of the frame 1.

At one side of the frame 1 is located the crank handle 17 which is fixed to one extremity of the shaft 18, the latter being operatively connected with the shaft 16 through the medium of meshing gears 19 and 20 which are fixed respectively to said shafts 15 and 18, as clearly shown in Figs. 14 and 15. Operative connection between the shafts 15 and 16 is effected through the medium of meshing pinions 21 and 22 which are respectively carried by said shafts, helical compression springs 23 being arranged under the movable bearings carrying the respective ends of the shaft 16 in order to maintain the pinion 22 in mesh with the pinion 21 and also the rollers 13 and 14 in yielding engagement with each other.

Rockingly mounted in the frame 1 below the plate 11 is a transversely extending shaft 45 24 to the respective ends of which are fixed upwardly extending arms 25 the upper ends of which slidably engage pivoted blocks 26 carried at the upper sides of the ends of said plate 11; the arrangement being such that upon oscillation of the shaft 24 and hence the arm 25, said plate will be reciprocated in the manner above mentioned to effect withdrawal of envelopes from the magazine 2. Fixed to the rearward extremity of the shaft 18, as clearly shown in Fig. 2, is a crank arm 27 to the free end of which is pivotally secured one extremity of a link 28, the opposite end of said link being adjustably secured by means of a screw or other connecting device 29 with one of the arms 25; an elongated slot 30 provided in said end of said link for engagement by the securing device 29 permitting of the adjustment mentioned. With this arrangement 60 then, it will be seen that upon rotation of

shaft 18 through the medium of the handle 17 in addition to rotation of the rollers 13 and 14, reciprocation of the envelop withdrawing plate 11 will also be simultaneously effected.

Arranged below the withdrawing plate 11 is a moistening device which is designed to apply moisture to the under side of the plate 11 at the front end portion thereof so that when said plate engages the flap of an envelop, the gummed side of said flap will be moistened and so that when said envelop is drawn from said plate by the roller 3 and the rollers 13 and 14, said flap will be pressed against the under side of the body of the envelop to effect sealing of the latter. This moistening device comprises an elongated rectangular well 31 one edge of which is provided at its extremities with angular notched plates 32 for pivotal engagement of inwardly projecting pins 33 provided at the opposite sides of the frame 1. The arrangement is such as will be observed, that the inner end portion of the well 31 is free for oscillation and so that when the same is rocked upwardly a strip 34 of absorbent material which is provided in said end of said well and which projects through an opening in the upper side thereof as clearly shown in Fig. 4 will be pressed into engagement with the under side of the plate 11 and apply moisture thereto as above mentioned. The pivot plates 32 so engage the pins 33 that said well may be readily removed if desired for adjusting the absorbent strip 34 or for filling the well with water, such filling being effected upon removal of a plug 35 provided in the top of said well as clearly shown in Fig. 10. Rocking of the free or inner end of the well 31 as just mentioned, is effected through the medium of a lever 37 which is fulcrumed intermediate its extremities as at 36 at one side of the frame 1 as shown in Fig. 9. The inner end of said lever normally rests by gravity upon a cushion 38 provided upon the transversely extending plate 39, said end of said plate terminating as to support the inner or free end of the well 31 so that the absorbent strip of the latter will normally rest in close proximity with the plate 11, although however, out of engagement therewith. The arrangement is such that when the outer end of said lever is depressed the inner end thereof upon being elevated, will elevate the inner end of the well 31 forcing the absorbent strip thereof into contact with said withdrawing plate 11 as above mentioned. Such rocking of the lever 37 is effected by the link 28 before mentioned, the end of said link which is connected with the arm 25 being adapted to contact a screw 40 provided in the outer end of the lever 37 when the arm 25 is at its outer terminal of oscillation and hence the plate 11 at its corresponding terminal of re- 130

ciprocation to effect lowering of the outer end of said lever 37 and hence elevation of the inner end thereof with the results as above described. Through the provision of said screw 40 it will be observed that adjustment is afforded whereby the amplitude of movement of the free end of the well 31 may be regulated.

Provided within the frame 1 at the opposite sides thereof immediately below the extremities of the plate 11 are levers 41 which are rockingly mounted intermediate their extremities upon screw studs 42 secured in frame 1, as clearly shown in Figs. 4 and 6. The inner ends of the levers 41 serve to support the respective extremities of the shaft 4 of the roller 3 so that when said levers are rocked said roller will be vertically moved. The inner extremities of the levers 41 are supported upon the upper end portions of vertically disposed levers 44 which are pivoted intermediate their extremities at 45. The upper ends of the levers 44 are formed each with two steps 44' and 44'', the inner ends of the levers 41 engaging the upper steps 44' when the roller 3 is at its upper terminal of movement, the same engaging the steps 44'' when said roller is at its lower terminal of movement. Provided adjacent the inner ends of the levers 41 are stops 41' which limit upward movement thereof. The outer or opposite extremities of the levers 41 are formed at their upper edges with inclined cam surfaces 41'' for engagement by the under side of the plate 11, the arrangement being such that when said plate is moved outwardly the extremities thereof will ride up on said cam surfaces 41'' and depress the outer extremities of the levers 41 so as to effect upward movement of the inner ends thereof and hence vertical movement of the roller 3. Tension springs 43 coöperate with the lower ends of the levers 44 so that when said levers 41 are so rocked by the plate 11, the upper ends of the levers 44 will be rocked so as to effect engagement of the steps 44' with said ends of said levers 41 in order to maintain the latter in this position and hence the roller 3 at its upper terminal of movement. When in this position the roller 3 is adapted to engage against the under side of the plate 11 and so that when an envelop is carried by said plate the flap of said envelop will be pressed tightly against the under side of said plate to insure moistening of the gum thereof by the moisture which is carried by said plate. When said plate reaches its inner terminal of movement the same will engage the upper extremities of the levers 44 and disengage the outer ends of the levers 41. The engagement of the levers 44 will effect rocking of the upper ends thereof to release the inner ends of the levers 41. Upon release of said ends of said levers 41

the roller 3 will by gravity move downwardly until the inner ends of the levers 41 will rest upon the steps 44'' of the levers 44, said roller 3 when in this position being out of engagement with the plate 11 and so that when the envelop is removed from the latter and carried forwardly by the rollers 13 and 14, the moisture remaining upon the under side of said plate will not be deposited upon said roller 3. Hence with this construction it will be seen that at each reciprocation of the plate 11 the roller 3 will be moved vertically in the manner and for the purpose described.

Upon leaving the sealing rollers 13 and 14 the envelop passes between superimposed rollers 46 and 47, the former being carried by the shaft 18 and the latter by a shaft 48 whose extremities are mounted in bearings provided in the sides of the frame 1, rotation of the roller 48 being effected through frictional contact with the roller 46. In order therefore to maintain a close engagement of the roller 47 with the roller 46 the extremities of the shaft 48 are engaged by helical compression springs 49 which serve to press the same downwardly and hence the roller 47 correspondingly into close contact with the upper side of the roller 46. The space between the sets of rollers 13 and 14 and 46 and 47 is spanned by bars 50 which are spaced apart, the extremities of said bars engaging circumferential grooves provided respectively in the rollers 14 and 46 as clearly illustrated in Figs. 3 and 4. Upon leaving the rollers 46 and 47 the envelops are deposited upon the inclined plate 51 extending transversely within the frame 1, the outer ends of the bars 50 serving as strippers to direct the envelops to said plate where the same are discharged from the machine upon the table or desk top or into a receptacle if desired, provided for the reception thereof.

In the passage of an envelop from the rollers 13 and 14 to the rollers 46 and 47, a stamp is applied thereto, the mechanism for effecting the application of the stamp to the envelop being set forth in the following.

Secured rigidly to one side of the frame 1 at the upper edge thereof and adjacent the rearward or discharge end of the machine is an inwardly projecting bracket 52, shown clearly in Figs. 13 and 14. Carried at the inner end of the bracket 52 is a horizontally disposed stamp-strip channel or guide 53, the same being of such a width as to be adapted to permit of the passage of a stamp of usual dimensions therethrough. Also secured to the bracket 52 is a rearwardly projecting arm 54 upon the free extremity of which is mounted a circular stamp strip or ribbon magazine 55, the loop 56 provided at one side of said magazine engaging said extremity of said arm 54 as clearly shown in

Fig. 12 last referred to. Arranged centrally within the magazine 55 is an arbor 57 upon which may be supported a stamp strip coiled thereon as shown in dotted lines in Fig. 13. The upper portion 58 of the magazine 55 is hingedly secured as at 59 to the lower or body portion of said magazine so as to permit of upward swinging of the former so as to gain access to the interior of the magazine in arranging a stamp strip coil upon the removably supported arbor 57. The outer end of the stamp strip 60 passes through the outer discharge opening 60' of the magazine entering the outer end of the channel or guide passage 53. Provided at the lateral edges of the channel 53 are longitudinally extending leaf springs 61 which are adapted to press against the upper sides of the lateral edges of the stamp strip so as to hold the latter flat upon and in close proximity with the bottom of said stamp passage 53. The outer ends of the springs 61 are connected with a yoke 62 which is rigidly secured to the guide 53 by means of screws 63.

Depending from the guide 53 at the lateral or longitudinal edges thereof are flanges 64 in which is mounted a transversely extending shaft 65, the outer end of the latter also projecting through the adjacent portion of the frame 1 as indicated in Fig. 7. Rising from the guide 53 at the inner end thereof is an inverted U-shaped supporting frame 66 in the upper end of which is mounted a rock shaft 67. The outer end of the rock shaft 67 terminates in a crank arm 68 as clearly shown in Figs. 7 and 12, the free extremity of said arm 68 loosely engaging an arcual slot 69 formed in the upper free end of a lever 70 which is fulcrumed at its lower end at 71 upon a bearing plate 72 rigidly secured to the outer one of the flanges 64. The arrangement is such as will be observed that oscillation of the lever 70 will impart corresponding oscillatory movement to the shaft 67. Projecting from one side of the lever 70 is a pin 73 which is positioned for engagement by the points of a three-pointed star wheel 74 carried by the shaft 65, so that when said shaft 65 is rotated the lever 70 and hence the shaft 67 will be oscillated, said star wheel being adapted to oscillate said lever and shaft three times at each complete rotation thereof.

Carried by the shaft 67 intermediate its extremities is a rocker arm 75 adjustably secured thereto by means of a set-screw 76. The free end of the arm 75 is operatively connected through the medium of a link 77 with a stamp strip feed 78 which embraces and is reciprocally mounted upon the guide 53. The arrangement is such as is apparent upon oscillation of the shaft 67 in the manner above set forth, the member 78 will be

reciprocated upon the guide 53. Pivotedly mounted in the upper side of the member 78 is a plurality of dogs or pawls 79 having their free ends pointed and disposed for normally engaging the bottom of the stamp passage 53. Said dogs 79 are so arranged as to be adapted when reciprocated to engage the perforations which separate the stamps of the stamp strip and so that when said dogs are reciprocated the stamp strip will be fed forwardly by said dogs upon forward movement of the latter. In order to insure a positive engagement of the dogs 79 with the perforations in the stamp strip the section 80 of the bottom of the stamp passage engaged by the dogs 79 is reciprocally mounted, said bottom of said passage in order to permit of such reciprocation being cut away as at 81. The section 80 is rigidly secured to the under side of the member 78 by means of screws or other securing devices 82 so that said section will move in unison with said member 78 and hence with the dogs 79. By this construction it will be seen that after engagement of the dogs with the perforations in the stamp strip such engagement will not be distributed; that is said dogs will not be moved out of engagement with said perforations except upon return movement thereof, it being clear that without the provision of the section 80 movably mounted as described, the ends of the dogs would be required to slide upon the bottom of the stamp passage and so that any unevenness of said surface might effect tripping of said dogs. With the construction as set forth this objection is obviated.

It will be observed that the star wheel 74 is adapted to effect oscillation of the lever 70 only in one direction and hence only forward movement of the stamp feeding mechanism; return movement of said lever and hence of the stamp feeding mechanism being effected through the medium of a torsional spring 83 which is mounted upon the rock shaft 67 as clearly shown in Fig. 7. Secured upon the upper side of the frame 66 is a strap 84 one end of which projects beyond and depends from one edge of the upper portion of said frame. Threaded in said end of said strap is a screw 85 the inner end of which is adapted to serve as a stop for the rocker arm 75 thereby serving to limit return movement of the stamp strip feeding mechanism. With this provision it will be seen that the amplitude of the reciprocation of the stamp feeding mechanism may be readily adjusted by simply adjusting said screw 85, thereby adapting the device for employment in conjunction with stamps of various lengths.

Mounted upon the upper side of the frame 66 is a registering device or meter 86, the actuating stem of which is provided with

70

100

105

110

115

120

125

130

a rocker arm 88. The free end of the latter is connected through the medium of a link 89 with a crank arm 89' provided at the rearward extremity of the rock shaft 67. 5 With this provision it will be observed that each actuation of the stamp feeding mechanism will be registered since each oscillation of the shaft 67 effects corresponding oscillation of the actuating shaft 87 of the 10 meter 86. This being so a register of the number of stamps affixed by the machine will be kept since upon each actuation of the stamp feeding mechanism the stamp strip is fed forwardly, a distance corresponding with the length of a stamp to position the terminal stamp for severance and application as will be described hereinafter.

Carried upon the outer end of the shaft 65 as clearly shown in Figs. 14 and 15 is 20 a star wheel 90 arranged adjacent the inner side of the gear 20 carried by the shaft 18. Loosely mounted in the gear 20 for transverse sliding movement therein, is a pin 91 adapted when at its inner terminal movement as shown in Fig. 14 to engage the 25 slots 92 provided in the periphery of the star wheel 90. Said star wheel is provided with three slots 92 which are spaced equidistant in the periphery thereof, the arrangement being such that upon each rotation 30 of the gear 20, the pin 91 thereof will be adapted to engage one of said slots 92 to rotate the wheel 90 through one third of a rotation or one hundred and twenty degrees. 35 As will be observed by reference to Fig. 15 the pin 91 upon rotation of the gear 20 will not engage directly with a slot 92, but will engage the periphery of said wheel 90 and partially rotate the latter by contact with the periphery thereof before sliding into engagement with the slot. Thus 40 an operative connection is established between the operating shaft 18 or the operating handle 17 and the stamp feeding mechanism so that upon each rotation of said handle the stamp feeding mechanism will be actuated to effect feeding of the stamp strip forwardly a distance equal to the 45 length of a stamp as above mentioned. Arranged adjacent the periphery of the wheel 90 is a spring detent 93 which is adapted to engage with projections 94 provided in the periphery of said wheel 90 in order to prevent movement of said wheel because of 50 inertia beyond its proper position when the device is being rapidly operated. The detent 93 serves as will be observed merely to yieldingly retard said star wheel, permitting of passage or rotation thereof when 55 sufficient force is exerted thereon as through the medium of the operating handle. The outer end of said detent is secured to the frame 1 by means of the screw 95, the latter engaging an elongated slot in said end 60 which obviously permits of adjustment of

detent in accordance with the projections upon the star wheel.

Arranged upon the frame 1 adjacent the lower side of the gear 20 is a spring cam plate 96 which is positioned in the path of the pin 91 as clearly shown in Fig. 15; 70 said cam plate being of such formation as to be adapted upon rotation of said gear 20 to engage the inner end of the pin 91 and force the same outwardly to inoperative position. Inward movement or forcing of said pin 91 is effected through the medium of a circular cam plate 97 which is loosely mounted upon the shaft 18 at the outer side of the gear 20, said plate being positioned for engagement with the outer extremity of said pin as clearly illustrated in Fig. 14. Said cam plate 97 is however adapted to effect such movement of said pin only when the same is at its inner terminal 80 of movement upon the shaft 18, such movement of said pin not being possible when said plate is at its outer terminal of movement. Hence with this arrangement it will be observed that upon rotation of the gear 20 the cam plate 96 will positively effect 85 movement of the pin 91 to inoperative position, said pin remaining in this position unless the cam plate 96 is positioned as above mentioned at its inner terminal of movement. Therefore with this construction when the machine is in operation the feeding mechanism will remain inoperative unless the cam plate 97 is properly positioned.

Projecting from the cam plate 97 is a 90 stem 98 which is connected through the medium of the connection 99 with a transversely extending rod 100 slidably mounted in the frame 1. Also mounted in the frame 1 above the rod 100 is a rod 101 adapted 95 for rocking movement in said frame. Depending from the rod 101 is an arm 102 the lower end of which terminates, as clearly shown in Fig. 6 in the path of an envelop fed through the device. The arrangement is such that rocking of the arm 102 and hence of the rod 101 will be effected by contact with the forward edge of an envelop carried by the plate 11, the latter being cut away as at 103 so that when an 100 envelop is not carried by said plate said arm will not be engaged and hence will not be actuated.

Fixed to the rearward extremity of the rod 101 as clearly shown in Fig. 2 is a lever 103', the free end of said lever being weighted in order to normally maintain the arm 102 in operative or traversing position. Arranged below the lever 103' and fulcrumed at 104 is a lever 105, one end of which is 105 engaged by a roller 106 carried by one end of the lever 103'; the arrangement being such that rocking of the lever 103' as is caused by an envelop engaging and rocking the arm 102 will effect lowering or down- 110 115 120 125 130

ward movement of the roller 106 into contact with the adjacent end of the lever 105 effecting depression thereof. The opposite end of the lever 105 is operatively connected through the medium of a link 107 with a bell crank 108, the latter being pivotally connected with the rearward end of the rod 100 as clearly shown in Fig. 5. The arrangement is such that upon rocking of the lever 105 as caused by contact of an envelop with the arm 102, the rod 100 through the medium of the link 107 and bell crank 108 (the latter being pivoted at 109) will effect lateral sliding of said rod 100. Such movement of the rod 100 effects as will be observed, inward sliding of the cam plate 97 to operative position as above described. With the construction then as last set forth, it will be observed that when the machine is in operation, the cam plate 97 will be moved to operative position and hence the stamp feeding mechanism actuated only upon the feeding of an envelop through the device since in such operation the cam plate 97 upon each rotation of the gear 20 will force the pin 91 outwardly, such pin forcing the cam plate 97 correspondingly outwardly to inoperative position. Said cam plate 97 will remain in this position, that is in inoperative position unless the same is moved to operative position by the rod 100. The rod 100 will remain inert except upon rocking of the rod 101 and which rocking is effected only by an envelop carried by the withdrawing plate 11 as above described. Having explained the construction and operation of the machine which deals with the withdrawal of the envelop from the envelop magazine and with the feeding thereof through the machine and also the construction for feeding the stamp strip toward a position for application of the stamps to the envelop in its passage through the machine, the construction by means of which the stamp is severed and applied to the envelop will next be described. Such construction is set forth in the following:

Secured to and projecting from the vertical portions or legs of the frame 66 are supporting arms 110 to the forward or outer extremities of which is secured a vertically disposed plate 111. The outer edge of the plate 111 is formed with a flange 112 which rests against the adjacent side of the frame 1, the same being rigidly secured thereto at 113. The plate 111 is provided with an opening 111' which registers with the outer end of the stamp strip passage 53 as clearly shown in Fig. 13, the stamp strip, when the machine is in operation being fed through said opening and there severed. Provided at the vertical edges of the plate 111 are channels or guide flanges 114 which embrace the base of a rectangular holder 115, the same being slidably mounted therein. The lower

edge of said base is provided with a knife edge 115' which is adapted, when said member 115 is moved downwardly upon the plate 111 to sever the stamp strip projecting through the opening 111'. The member 115 is carried by an angular operating bar 116, the lower or vertically extending portion of said bar being slidably mounted in guide lugs 117 formed upon the adjacent side of frame 1 as clearly illustrated in Figs. 5, 14 and 15. The upper horizontally disposed end of the bar 116 projects over the upper end of the member 115, the same being secured thereto by means of a strap 118 which engages thereover. The adjacent side of the member 115 registering with the opening between the sides or ends of the strap 118 is slotted so as to permit of relative vertical movement of said bar 116, a compression spring 119 being arranged for engagement with the under side of said bar to normally maintain the member 115 in the position relative to said bar as shown in Fig. 12. Slidably mounted within the holder 115 is a plunger 120 which is secured to the lower end of a vertically slotted stem 121, the upper end of the latter engaging over the bar 116 as clearly shown in Fig. 13. A helical compression spring 122 interposed between the under side of said bar 116 and the upper side of the plunger 120 serves to normally maintain the latter in the position relative to said bar as shown in Fig. 13. It will be observed that the lower end of the plunger 120 is normally positioned above the lower extremity of the holder 115, said plunger however being permitted by reason of the yielding connection of the latter with the bar 116 to be lowered to register with the lower extremity of said holder when the latter has been brought to a stop in the manner hereinafter set forth.

Fulcrumed at 123 upon the front side of the frame 1 adjacent the gear 20 is a lever 124, the free end of said lever being operatively connected by means of a link 125 with the operating member 116 so that depression or downward movement of said member 116 in order to effect corresponding movement of the holder 115 and the parts connected therewith, (which constitute the stamp affixing or applying mechanism) will be effected by downward rocking of said end of said lever. Cooperating with said lever is a torsional spring 126 which is adapted normally to maintain the same and hence the operating bar 116 at its upper terminal of movement. By reference to Figs. 14 and 15 it will be observed that the lever 124 is disposed in the path of the pin 91 so that upon rotation of the gear 20, as above described, while referring to the stamp feeding mechanism, said pin will be adapted to engage and effect depression or downward rocking of said lever as mentioned. Fur-

ther, the construction is such that said lever will be depressed by said pin only when the latter is positioned at its inner terminal of movement so that said lever will be operated only when the star wheel 90 and hence the stamp feeding mechanism is operated, such operation being clearly set forth above.

Arranged forward of the rollers 14 and 15 directly below the stamp applying mechanism, is a table 127 preferably provided with a rubber covering at its top, as shown in Fig. 6. Said table is so positioned that in operation of the device, one end of the envelop will in its passage from between the rollers 14 and 15 be drawn across the upper side thereof. The downward movement of the member 115 as caused by the lever 124 through operation by the pin 91 is such as to bring the former into engagement with the upper side of said table or into contact with an envelop which may be positioned thereon and so that upon such movement of said holder when the device is in operation, the stamp which is severed thereby, providing the latter has been moistened, will be applied to the envelop by the plunger 120 which is forcibly pressed against the envelop.

Slidably mounted upon the upper edge 29 of the front side of the frame 1 adjacent the envelop magazine is a channel member 128 upon which is fulcrumed at 128' intermediate its extremities a lever 129, one half of said lever being positioned at the inner side of the frame member and the other half at the outer side thereof. Carried at the inner end of the lever 129, as shown in Fig. 6, is a rectangular well 130 in the forward end of which is provided a strip 131 of absorbent material which projects through an opening in the upper side of said well; access to the interior of said well for filling being afforded through a removable plug 132. The well 130 is positioned for registration with the stamp discharge opening 111', so that when the stamp is projected from said opening the absorbent strip 131 will be rocked into engagement with the gummed side thereof to effect moistening thereof in the manner set forth in the following. Provided at the free extremity of the outer end of the lever 129 is a roller 133, see particularly Fig. 1. Said roller is so positioned that upon reciprocation of the envelop withdrawing plate 11, the outer edge of one extremity of said plate will upon return movement of the latter engage said roller to effect slight depression thereof and corresponding movement of the lever 129. In this connection however, a dog 134 which is pivoted at 135 cooperates with the outer end of said lever 129. The free end of the dog 134 engages a pin 136 projecting from the adjacent side of the frame 1, said pin by engagement with an

elongated slot in said dog limiting the oscillatory movement thereof. The construction is such that when the lever 129 is at its inner terminal of movement the outer extremity thereof will release the free end of the dog 134 permitting of the latter dropping to the position as shown in Fig. 1.

Upon return movement of the plate 11 and engagement of the latter with the roller 133, said dog will retard the movement of 75 said lever so that continued movement of the plate 11 toward the roller 133 will effect depression of the latter and hence of the corresponding end of the lever to a position below the free end of the dog when said 80 lever will be moved along with the plate 11, the outer edge of the plate 11 being then brought into engagement with the depending portion at the outer extremity of the lever 129 to which said roller is secured. 85 Such depression of the outer end of said lever 129 obviously effects corresponding upward movement of the inner end thereof and hence of the well 130, such movement of the latter bringing the absorbent strip 90 131 into engagement with the portion of the stamp strip projecting from the opening 111'. Upon the outward movement of the lever 129 as mentioned, said absorbent strip will evidently be drawn across the under or 95 gummed surface of the stamp strip licking the same preparatory to application to the envelop. Forward movement of the lever, that is toward the stamp is effected by the plate 11 engaging a depending arm 100 137 secured to the member 128. Also secured to the member 128 is a flexible arm 138 at the inner extremity of which is carried a plate or jaw 139 positioned for co-operation with the absorbent strip 131 of 105 the well 130. Said plate 139 is moved simultaneously with said well and is adapted by means of a leaf spring 140 which engages with the arm 138 to be forced downwardly 110 into engagement with the upper side of the stamp when said well is forced upwardly into engagement with the under side, thus affording means for positively effecting moistening of the stamp, since said plate 139 will obviously serve to force the stamp 115 into close engagement with the absorbent strip the spring 140 in this operation, when the arm 138 is brought into contact therewith, serving to flex the free end of the latter downwardly.

The mechanism is so timed that when in operation the stamp strip will first be projected by the feeding mechanism through the opening 111'. The licking or moistening mechanism will then be brought into play to effect the licking or moistening of the stamp or portion of the stamp strip projecting from said opening. Upon return movement of the licking mechanism the stamp applying or affixing mechanism will 125 130

be lowered effecting the severing of the stamp and the application thereof to the envelop which will have been brought to such a position by the withdrawing plate and the feeding rollers that the stamp will be properly positioned thereon.

By reason of the provision above described whereby the stamp feeding and cutting and applying mechanism will be operated only when an envelop is withdrawn from the envelop magazine and fed through the device, provision is made whereby stamps will not be uselessly severed and wasted. In order to notify the operator of the device when the stamps have given out, that is when the entire roll has been used, the following provision is made: a supporting arm 141 is secured to the front side of the frame 1 at the upper edge thereof directly above the stamp strip guide 58 as clearly shown in Figs. 3 and 12, said arm being insulated from said frame. Mounted in said arm centrally of the guide 58 is an electrical contact 142, the same being so arranged that the free end thereof is adapted to rest upon the upper side of the stamp strip as it passes through said guide, and so that when the extremity of the stamp strip has passed the same, said end of said contact will drop to engagement with the bottom of said guide. The arm 141 is connected by means of the wire 143 with one of the terminals of an electrical bell or buzzer 149, the other terminal of the latter being connected by means of the wire 145 with a storage battery 146 which is grounded to the frame 1. With this arrangement it will be observed that while the contact 142 is resting upon the stamp strip, the electrical circuit will be broken thereby, the circuit being closed when said contact drops to engagement with the bottom of the stamp guide since the latter through the frame 1 is connected with the battery. With this arrangement then it will be observed that when the inner end of the stamp strip passes the contact 142 the circuit will be closed causing the sounding of the alarm, that is of the bell or buzzer 149 notifying the operator of this fact.

A device of the construction as set forth is durable and positive in its operation and through its employment envelopes may be easily stamped with great expedition.

While I have illustrated and described the preferred form for carrying my invention into effect, this is capable of variation and modification without departing from the spirit of the invention. I therefore do not wish to be limited to the precise details of construction set forth, but desire to avail myself of such variations and modifications as come within the scope of the appended claims.

Having described my invention what I

claim as new and desire to secure by Letters Patent is:

1. In a stamp affixing and envelop sealing machine, the combination of an envelop magazine, reciprocatory mechanism for automatically withdrawing an envelop from the bottom of said magazine and for sealing the flap thereof; manually operated gearing; a positive operative connection between said gearing and said envelop withdrawing and sealing means; stamp feeding and cutting mechanism; means for establishing an operative connection between said gearing and said stamp feeding and cutting mechanism; and oscillatory means projecting entirely across the path of said envelop withdrawing mechanism for actuating said last mentioned means for establishing said operative connection, said oscillatory means being adapted to be operated only when an envelop is carried by said envelop withdrawing mechanism, substantially as described.

2. In a stamp affixing and envelop sealing machine, the combination of an envelop magazine; a reciprocatory plate for withdrawing an envelop from said magazine; manually operated gearing; a positive operative connection between said gearing and said envelop withdrawing plate; stamp feeding and cutting mechanism; means for establishing an operative connection between said driving gearing and said stamp feeding and cutting mechanism; oscillatory means comprising an arm projecting downwardly across the path of said envelop withdrawing plate adapted when oscillated to actuate said last mentioned means to establish said operative connection, said oscillatory means being so positioned that the same will be engaged and oscillated only by an envelop carried by said envelop withdrawing plate, substantially as described.

3. In a stamp affixing and envelop sealing machine, the combination of an envelop magazine; a reciprocatory plate for withdrawing an envelop from said magazine; a moistening device adapted to be rocked into engagement with the under side of said plate to apply moisture thereto; driving means; an operative connection between said driving means and said envelop withdrawing plate; a moistening device; stamp feeding and cutting mechanism; means for establishing an operative connection between said driving means and said stamp feeding and cutting mechanism; and means operative by an envelop carried by said envelop withdrawing plate and comprising an arm projecting downwardly across the path of the envelop for actuating said last-named means to establish said operative connection, substantially as described.

4. In a stamp affixing and envelop sealing machine, the combination of an envelop

- magazine; a flat smooth reciprocatory plate arranged below said magazine adapted to engage under the flap of the lowermost envelop in said magazine to withdraw said envelop therefrom; a moistening device adapted to be rocked into engagement with the under side of said plate to apply moisture thereto; driving gearing; a positive operative connection between said gearing and said envelop withdrawing plate and moistening device; rollers for sealing the envelop flap; stamp feeding and cutting mechanism; means for establishing an operative connection between said driving gearing and said stamp feeding and cutting mechanism; and oscillatory means operative by an envelop carried by said envelop withdrawing plate for actuating said last-named means to establish said operative connection, substantially as described. 20
5. In a stamp affixing and envelop sealing machine, the combination of an envelop magazine; a reciprocatory plate arranged below said magazine adapted to engage under the flap of the lowermost envelop in said magazine to withdraw said envelop therefrom; a moistening device adapted to be rocked into engagement with the under side of said plate to apply moisture thereto; driving gearing; a positive operative connection between said gearing and said envelop withdrawing plate and moistening device; rollers for sealing the envelop flap; stamp feeding and cutting mechanism; means for establishing an operative connection between said driving gearing and said stamp feeding and cutting mechanism; oscillatory means operative by an envelop carried by said envelop withdrawing plate for actuating said last-named means to establish said operative connection, and a reciprocatory stamp moistening device positively connected with said driving gearing, substantially as described. 40
6. In a stamp affixing machine, the combination of an envelop magazine; a reciprocatory plate for withdrawing an envelop from said magazine; driving gearing positively connected with said envelop withdrawing plate; a stamp magazine adapted to hold a strip of stamps; reciprocatory means for feeding said stamp strip from said stamp magazine; a cutter adapted to sever the stamps from said strip; means for establishing an operative connection between said gearing and said stamp feeding and cutting mechanism; and means co-operative with the withdrawing plate for actuating said last mentioned means, substantially as described. 55
7. In a stamp affixing machine, the combination of an envelop magazine; a reciprocatory plate for withdrawing envelopes from said magazine; driving gearing operatively connected with said envelop withdrawing plate; a stamp magazine adapted to hold a strip of stamps; a stamp cutting and applying mechanism; reciprocatory means adapted to engage the perforations in said stamp strip between adjacent stamps for feeding the latter from said stamp magazine toward said cutting and applying mechanism; a star wheel adapted when rotated to actuate said stamp feeding mechanism; a lever adapted when rocked to actuate said stamp cutting and applying mechanism; a pin carried by said operating gearing adapted to rotate said star wheel and to rock said lever; means for normally positioning said pin in inoperative position; and means co-operative with the withdrawing means for moving said pin into operative position, substantially as described. 65
8. In a stamp affixing machine, the combination of an envelop magazine; means for withdrawing an envelop from said magazine; operating gearing operatively connected with said envelop withdrawing means; a stamp magazine adapted to hold a strip of stamps; a stamp cutting and applying mechanism; reciprocatory means adapted to engage the perforations in said stamp strip between adjacent stamps for feeding the latter from said stamp magazine toward said cutting and applying mechanism; means for establishing an operative connection between said operating gearing and said stamp feeding and applying mechanism; and means co-operative with the withdrawing means for moving said pin into operative position, substantially as described. 80
9. In a stamp affixing machine, the combination of an envelop magazine; means for withdrawing an envelop from said magazine; operating gearing operatively connected with said envelop withdrawing means; a stamp magazine adapted to hold a strip of stamps coiled therein; a stamp cutting and applying mechanism mounted for reciprocation transversely of said stamp strip; reciprocatory means adapted to engage the perforations in said stamp strip between adjacent stamps for feeding the latter from said stamp magazine toward said cutting and applying mechanism; a star wheel adapted when rotated to actuate said stamp feeding mechanism; a lever adapted when rocked to actuate said stamp cutting and applying mechanism; a pin carried by said operating gearing adapted to rotate said star wheel and to rock said lever; means for normally positioning said pin in inoperative position; and means co-operative with the withdrawing means for moving said pin into operative position, substantially as described. 100
10. In a stamp affixing machine, the combination of an envelop magazine; means for withdrawing an envelop from said magazine; operating gearing operatively connected with said envelop withdrawing means; a stamp magazine adapted to hold a strip of stamps; a stamp cutting and applying mechanism; reciprocatory means adapted to engage the perforations in said stamp strip between adjacent stamps for feeding the latter from said stamp magazine toward said cutting and applying mechanism; a star wheel adapted when rotated to actuate said stamp feeding mechanism; a lever adapted when rocked to actuate said stamp cutting and applying mechanism; a pin carried by said operating gearing adapted to rotate said star wheel and to rock said lever; means for normally positioning said pin in inoperative position; and means co-operative with the withdrawing means for moving said pin into operative position, substantially as described. 115

ter from said stamp magazine toward said cutting and applying mechanism; means for establishing an operative connection between said operating gearing and said 5 stamp feeding and applying mechanism; means coöperative with the withdrawing means for actuating said last mentioned means, substantially as described.

11. In a stamp affixing machine, the combination of an envelop magazine; means for withdrawing an envelop from said magazine; operating gearing operatively connected with said envelop withdrawing means; a stamp magazine adapted to hold 10 a strip of stamps; a stamp cutting and applying mechanism; reciprocatory means adapted to engage the perforations in said stamp strip between adjacent stamps for feeding the latter from said stamp magazine 15 toward said cutting and applying mechanism; means for establishing an operative connection between said operating gearing and said stamp feeding and applying mechanism; means coöperative with the withdrawing means for actuating said last mentioned means; substantially as described.

12. In a stamp affixing machine, the combination of an envelop magazine; means for withdrawing an envelop from said magazine; operating gearing operatively connected with said envelop withdrawing means; a stamp magazine adapted to hold a strip 20 of stamps; a stamp cutting and applying mechanism; reciprocatory means adapted to engage the perforations in said stamp strip between adjacent stamps for feeding the latter from said stamp magazine toward said cutting and applying mechanism; means for establishing an operative connection between said operating gearing and said stamp feeding and applying mechanism; means coöperative with the withdrawing means for actuating said last mentioned means; a registering device operatively connected with 25 said feeding mechanism; substantially as described.

13. In a stamp affixing machine, the combination with stamp strip feeding mechanism, a severing and stamp applying mechanism, and 30 means for manually operating said mecha-

nisms, of means for moistening the end of said strip prior to severance by said severing mechanism, said means comprising a reciprocatory well having an absorbent strip projecting from its upper side adapted to engage 35 and be drawn across the under side of the stamp; said absorbent strip assuming a position below said stamp in its movement toward the same; means for elevating said strip into contact with the stamp when positioned 40 directly below the same and for maintaining said strip in this position; a jaw coöperating with said absorbent strip and adapted to engage against the upper side of the stamp; said jaw assuming a position above the 45 stamp in its movement toward the same; means for forcing said jaw into engagement with the stamp when positioned directly over the same; and an operative connection between said moistening well and jaw and 50 said operating means, substantially as described.

14. In a stamp affixing machine, the combination with an envelop magazine and envelop sealing and feeding rolls of means 55 comprising a reciprocatory plate for feeding single envelops from the magazine to the rolls, a stamp feeding and affixing mechanism and driving means therefor and means projecting downwardly across the 60 path of the envelop but out of contact with the envelop feeding plate for connecting the stamp feeding and affixing means with the envelop feeding means and means comprising a reciprocatory spring stamp contacting jaw and a reciprocatory and rocking stamp moistening pad for holding and moistening stamps, means responsive to the reciprocation of said plate for reciprocating said jaw and said pad and for pressing 65 said pad against the under side of the stamp to hold it against the jaw during its movement away from the stamp.

In testimony whereof I have signed my name to this specification in the presence of 70 two subscribing witnesses.

EDWARD J. ABBOTT.
